PRINTING LAMP AND CYLINDER
COOLING MEANSFrederick O. Trump, Binghamton, N. Y., assignor
to General Aniline & Film Corporation, New
York, N. Y., a corporation of Delaware

Application April 11, 1951, Serial No. 220,474

5 Claims. (Cl. 95—77.5)

1
This invention relates to air cooling arrangements for printing light assemblies employing high intensity light sources, such as mercury vapor lamps.

This application is a continuation-in-part of my application Serial No. 13,995, filed March 10, 1948, for Printing Lamp and Cylinder Cooling Means, now abandoned.

The type of contact printing apparatus to which this invention is particularly directed produces rapid photo-contact prints on diazo sensitized material which requires a high intensity mercury vapor, a similar discharge lamp, in order to obtain sufficient light in a particular spectral range, in the region of violet and ultra-violet of approximately 3600 Å units. Such lamps are generally housed in a rotating transparent cylinder of pyrex or other heat resisting glass, over which the sensitized material, in contact with the original to be printed, is passed. The heat generated by the lamp confined in this cylinder is excessive for its safe operation as well as for the temperature of the cylinder wall which is in intimate contact with the sensitized paper.

The problem confronting the designer of a cooling arrangement for such apparatus is that the printing cylinder must be operated at a much lower temperature than the lamp. The latter, by its necessary physical placement in the cylinder, generates an intense heat and must not be cooled below a certain minimum temperature for efficient light rendition in the required spectrum. This minimum temperature, on the other hand, is far in excess to that which the printing cylinder may have for satisfactory operation.

In order to overcome the above difficulties, it has been the practice to completely enclose the lamp itself in a transparent heat resistant glass tube, thereby isolating the printing cylinder from the lamp. Then, air is circulated within the glass tube and about the lamp, thereby to cool it to a safe temperature while a separate mass of air is employed to cool the printing cylinder itself to a temperature which is safe insofar as the sensitized material is concerned. This construction is cumbersome and costly, and often results in over-cooling of the lamp. Moreover, the additional glass tube is another barrier to the shorter wavelengths of light. Therefore, it reduces the illumination, and also isolates the lamp, making it more difficult to clean. In fact, such smaller heat resistant glass tubes have been found to reduce the radiation to such an extent as to lower the printing speed approximately 25-30%.

The object of this invention is to provide a

2
cooling arrangement for such light assemblies which will distribute the cooling air in such manner as to maintain the printing cylinder at the proper temperature and permit operation of the lamp at higher temperatures for maximum light efficiency.

A particular feature of the invention is that the efficiency of the printing apparatus is considerably increased by permitting unobstructed passage of light between the lamp and an active exposure surface of the cylinder, although the cylinder is effectively heat shielded from the lamp.

Other objects and features will be apparent from the following description of the invention, defined in particularity in the appended claims, and taken in connection with the accompanying drawing, in which:

Figure 1 is a perspective view of the light assembly, certain parts being cut away to show the interior of the construction;

Figure 2 is a transverse section taken through the center of the assembly illustrated in Figure 1.

In accordance with the invention, a heat resistant glass shield, partially surrounding the lamp, is supported in combination with a reflector and a suction duct. The shield forms a heat deflector between the lamp and the print exposure portion of the cylinder. Cooling of the lamp and the interior of the printing cylinder is effected through the air currents produced by suction in the cooling duct. Little of the radiant energy is lost, since the open portion of the partial shield in combination with the reflector permits unobstructed passage of light to an active exposure surface of the cylinder.

The duct maintained under a fairly high vacuum is provided with a series of apertures, some of which draw air from the vicinity of the lamp and its deflector shield, while other apertures in the duct draw air from the interior surface of the printing cylinder, so that a differential temperature is created between these surfaces, although the lamp itself is not isolated.

By the use of this printing light assembly, hereinafter described in greater detail, it is possible to reduce the temperature of the printing cylinder by approximately 20° F. more than heretofore, without affecting the light intensity and thereby the printing speed of the apparatus.

The shield extends below the lamp thereby preventing contact of the cooler air inside the printing cylinder with the lower portion of the lamp which is most critical to cooling. The fact that the assembly is easily accessible for cleaning is an added advantage, since it has been found that

accumulation of dust may reduce light output by as much as 30%.

Now referring to the figures, a cylinder 10, generally made of a heat resistant transparent glass, is rotatably mounted at each end on rollers 11 or other suitable bearings, schematically shown here. This cylinder is so mounted in the printing apparatus as to be rotated by a plurality of tapes or belts which serve to guide and direct the sensitized material and the original to be printed about and in contact with the cylinder. The sensitized material is printed by the action of light passing through the cylinder and emitted from a centrally disposed tubular mercury vapor lamp 12.

The lamp 12 may be supported at each end by means not illustrated in detail here, but shown in U. S. Patent 2,308,130.

An elongated air duct 13, having a flat front wall 14 and a curved rear wall 15, is constructed in such manner that it extends within the printing cylinder 10, being positioned to one side from the center line, more specifically, at the side of the cylinder opposite to the exposure surface about which the sensitized material is passed. The duct 13 is closed at both ends and extends beyond the cylinder at one end which has an exhaust outlet 16, to which may be attached a suitable flexible tube connecting the outlet 16 to a pump or other device adapted to exhaust air from its interior.

The duct 13 has a series of air inlet openings 17, centrally located in the front wall 14, and a number of similar openings 18 disposed in the rear wall 15. These openings, or apertures, are spaced along the length of the walls and serve to admit the heated air adjacent thereto, so that it may be drawn out by the suction through the outlet 16.

A convex reflector 19 is attached to the front wall 14 of the duct and serves to reflect radiation from the lamp 12 toward the exposure surface of the printing cylinder 10 with which the sensitized material and the original to be printed are in contact. This reflector also has a plurality of apertures 20 in alignment with the series of openings 17, through which heated air from the vicinity of the lamp 12 is drawn into the duct 13.

A shield 21 extending along the length of the lamp 12 is held in position by brackets 22 mounted on the reflector 19, one of which is positioned at either end of the assembly. The shield 21 is semicylindrical and made of heat resistant transparent glass. It surrounds the lamp 12 in an arc of approximately 180°, and forms a heat deflector between the lamp and the printing cylinder. The shield 21 passes beneath the lamp 12 and extends to the adjacent face of the reflector 19, so as to completely cover the lower portion of the lamp and thereby prevent overcooling thereof.

It is to be noted that the top of the lamp is not shielded so that an unobstructed passage of light is provided in the space intervening between the top edge of the shield and the reflector 19.

In operation, the vacuum created within the duct 13 causes air to enter at both ends of the printing cylinder 10, and pass through the openings 17, 18 and 20. The curved wall 15 of the duct 13 is close to the inner wall of the rotating cylinder 10, and a high velocity strong air current is created over this surface. Heat radiation from the lamp 12, by virtue of the shield 21, is sufficiently restricted and will not affect the cooling of the rotating cylinder 10. The cooling air from both ends of the cylinder finds passage around

the lamp to enter the openings 20 in the reflector and from there the openings 17 in the duct. The velocity of the air over this passage is far lower than through openings 18, but sufficient to cool the lamp to the required temperature. The cooling is chiefly over the top portion of the lamp 12 where the open space and the curvature of the shield produces turbulence and a down draft due to the suction.

A small portion of the radiation emitted is absorbed by the shield 21, however, the appreciable space at the top of the lamp supplemented by the reflector 19 permits relatively effective use of the total illumination from the lamp.

The entire combination has been found to be very effective, since, by this means, the lamp may be operated at its most efficient temperature, and, at the same time, it can be enclosed in a relatively small printing cylinder operated at a temperature low enough to permit the printing of all diazo-coated materials without damage to the coating thereof. Of course, it is desirable to keep the printing cylinder 10 down to a relatively small diameter since the radiation from the lamp falls off in the usual proportion as the distance to the material to be printed is increased.

In the description, certain angular extents of parts have been referred to by way of example. It is to be understood that reasonable variation in the proportions and in the angular extent to which the shield surrounds the lamp may be made without departing from the inventive concept and without altering the general effectiveness of the combination itself. The actual shape of parts, for example, the curvature of the reflector, the actual design of the suction duct and the number and size of apertures through which the heated air is drawn into the duct may all be altered within limits depending upon the size of the printing cylinder, the actual size and design of the lamp itself, and other pertinent factors. In the event the cylinder and lamp are of extreme length, as in larger machines, the duct may preferably be provided with outlet connections 16 at both ends and may be designed in such manner as to draw in the heated air more evenly along its entire length, thereby to cool the parts equally at all points and to avoid excessive heat in the cylinder at its localized areas.

50 I claim:

1. Cooling arrangement for printing light assembly for contact printing apparatus of the type utilizing a transparent open ended rotating printing cylinder about which the sensitized material in contact with the original is passed and exposed including a tubular high intensity lamp axially disposed within said cylinder; comprising, at one side from said lamp, a reflector having a plurality of air intake openings extending adjacent said lamp, an elongated air duct behind said reflector closed at both ends, an exhaust outlet therefor, said duct having in one side a plurality of air intake openings in alignment with said intake openings in said reflector, and in the opposite side intake openings facing the inner wall of said cylinder, and at the other side from said lamp a transparent semicylindrical shield extending along the length of said lamp, said shield forming a heat deflector between said lamp and the cylinder wall and providing distribution of cooling air over said lamp while permitting unobstructed passage of light between said lamp and an active exposure surface of said cylinder.

75 2. Cooling arrangement for printing light as-

sembly for contact printing apparatus of the type utilizing a transparent open ended rotating printing cylinder about which the sensitized material in contact with the original is passed and exposed including a tubular high intensity lamp axially disposed within said cylinder; comprising, at one side from said lamp, a reflector having a plurality of air intake openings extending adjacent said lamp, an elongated air duct behind said reflector closed at both ends, an exhaust outlet therefor, said duct having in one side a plurality of air intake openings in alignment with said intake openings in said reflector, and in the opposite side intake openings facing the inner wall of said cylinder, and at the other side from said lamp a transparent semicylindrical shield extending along the length of said lamp, said shield forming a heat deflector between said lamp and the print exposure wall of said cylinder and providing distribution of cooling air over said lamp while permitting unobstructed passage of light between said lamp and a portion of the active exposure surface of said cylinder.

3. Cooling arrangement for printing light assembly for contact printing apparatus of the type utilizing a transparent open ended rotating printing cylinder about which the sensitized material in contact with the original is passed and exposed including a tubular high intensity lamp axially disposed within said cylinder; comprising, at one side from said lamp, a convex reflector having a plurality of air intake openings extending adjacent said lamp, an elongated air duct behind said reflector and forming a support thereof, said duct being closed at both ends, an exhaust outlet therefor, said duct having in one side a plurality of air intake openings in alignment with said intake openings in said reflector, and in the opposite side intake openings facing the inner wall of said cylinder, whereby suction through said openings removes the heated air near said lamp and at the other side from said lamp said cylinder wall, and a transparent semicylindrical shield extending along the length of said lamp, said shield forming a heat deflector between said lamp and the print exposure wall of said cylinder and providing distribution of cooling air over said lamp while permitting unobstructed passage of light between said lamp and a portion of the active exposure surface of said cylinder.

4. Cooling arrangement for printing light assembly for contact printing apparatus of the type utilizing a transparent open ended rotating printing cylinder about which the sensitized material in contact with the original is passed and exposed including a tubular high intensity mercury vapor

lamp axially disposed within said cylinder; comprising, at one side from said lamp, a convex reflector having a plurality of air intake openings extending adjacent said lamp, an elongated air duct having a flat wall adjacent said reflector and forming a support thereof, and having a curved wall adjacent the inner wall of said cylinder, said duct being closed at both ends, an exhaust outlet therefor, said flat wall having a plurality of air intake openings in alignment with said intake openings in said reflector, and said curved wall having intake openings distributed over its surface, and at the other side from said lamp a transparent semicylindrical glass shield extending along the length of said lamp, said shield forming a heat deflector between said lamp and the print exposure wall of said cylinder and providing distribution of cooling air over said lamp while permitting unobstructed passage of light between said lamp and a portion of the active exposure surface of said cylinder.

5. Cooling arrangement for printing light assembly for contact printing apparatus of the type utilizing a transparent open ended rotating printing cylinder about which the sensitized material in contact with the original is passed and exposed including a tubular high intensity mercury vapor lamp axially disposed within said cylinder; comprising, at one side from said lamp, a convex reflector having a plurality of air intake openings extending adjacent said lamp, an elongated air duct having a flat wall adjacent said reflector and forming a support thereof, and having a curved wall adjacent the inner wall of said cylinder, said duct being closed at both ends, an exhaust outlet therefor, said flat wall having a plurality of air intake openings in alignment with said intake openings in said reflector, and said curved wall having intake openings distributed over its surface, and at the other side from said lamp a transparent semicylindrical glass shield partially surrounding said lamp, the bottom edge of said shield engaging said reflector, said shield forming a heat deflector between said lamp and the print exposure wall of said cylinder and providing distribution of cooling air over said lamp while permitting unobstructed passage of light between said lamp and a portion of the active exposure surface of said cylinder.
